UNITED STATES PATENT OFFICE.

FRANK B. MARTIN, OF BATTLE CREEK, MICHIGAN, ASSIGNOR TO POSTUM CEREAL CO., LIMITED, OF BATTLE CREEK, MICHIGAN, A COPARTNERSHIP OF MICHIGAN.

CARTON-FEEDING MECHANISM.

1,137,227.

Specification of Letters Patent. Patented Apr. 27, 1915.

Application filed October 27, 1910. Serial No. 589,426.

To all whom it may concern:

Be it known that I, FRANK B. MARTIN, a citizen of the United States, residing at Battle Creek, in the county of Calhoun and 5 State of Michigan, have invented certain new and useful Improvements in Carton-Feeding Mechanism; and I do declare the following to be a full, clear, and exact description of the invention, such as will enable others skilled in the art to which it 10 pertains to make and use the same.

My invention relates to improvements in machines for sealing the end flaps of cartons or other receptacles and more particularly 15 to conveyers employed in such machines for feeding the cartons or other receptacles to and past the carton sealing mechanism.

The object of the invention is to provide 20 means for feeding a plurality of streams of cartons to the carton sealing mechanism which streams shall be actuated by a single conveyer to the end that the capacity of such machines may be largely increased and the compactness and cost of the machine maintained at the minimum while the efficiency 25 of the operation of the machine shall be greatly increased.

With this object in view, the invention 30 consists of a plurality of tracks or ways, preferably two, provided with means for guiding the cartons along said tracks or ways, and a single conveyer, such as a chain with suitably spaced followers thereon, for moving the cartons along said ways to and 35 past the sealing mechanism, and a plurality of feed devices for supplying streams of cartons to said ways combined with means for simultaneously shifting one carton from one feed device to one of the said ways and 40 another carton from the other feed device to the other way, to the end that two cartons, one in each way, may be simultaneously advanced by a single follower on the conveyer.

The invention further consists in certain 45 features of novelty and construction and arrangement of parts hereinafter fully described and claimed.

The invention is capable of receiving a 50 variety of mechanical expressions one of which, for the purpose of illustrating the invention, is shown in the accompanying drawings, but it is to be understood that such drawings are for the purpose of aiding in the description of the invention and are 55 not designed to define the limits thereof,

reference being had to the claims hereto appended for that purpose.

In the drawings—Figures 1 and 1^a are side views of the rear and front end portions of the machine, Fig. 1^a being a continuation of Fig. 1. Figs. 2 and 2^a are plan views of the parts shown in Figs. 1 and 1^a, respectively, some of the feeding rollers being omitted in Fig. 2. Fig. 3 is an enlarged detail plan view showing the mechanism for shifting the cartons laterally from the feeding belts on to the supporting plates. Figs. 4 and 5 are detail transverse sectional views through the parts shown in Fig. 3, the lateral push members being shown in retracted 60 position in Fig. 4, and in inwardly projected position in Fig. 5. Fig. 6 is a detail horizontal section through one of the links or rods which operate the lateral push members. Fig. 7 is a side view of one end of 70 the link or rod shown in Fig. 12. Fig. 8 is a detail sectional view through the rear or discharge end of the main conveyer or carrier. Fig. 9 is a plan view of one of the 75 carton followers and a portion of the main conveyer chain. Fig. 10 is a detail perspective view of one of the followers. Fig. 11 is a detail cross sectional view taken on line 17—17 of Fig. 1. Fig. 12 is a detail cross 80 sectional view showing the manner of 85 mounting the carton guide rails at the front or receiving end of the machine. Fig. 13 is a similar cross sectional view showing the manner of mounting the carton guiding rollers at the central and discharge end of the 90 machine. Fig. 14 is a detail perspective 95 view showing a hand retracted stop which may be used over the feed belts at the front end of the machine for stopping the feeding of cartons to the lateral push members.

Referring to the drawings, 1 is a main frame of any suitable form or construction upon which is mounted any desired carton sealing mechanism and upon which frame is also mounted the carton conveyer for feeding or supplying cartons to said mechanism. As illustrated said frame preferably comprises the uprights 2 supporting upper side bars 3 and lower side bars 4. Other connecting bars and braces are also preferably employed as illustrated to provide a rigid supporting structure.

Arranged to travel longitudinally through the main frame is a main carrier or conveyer, preferably in the form of a sprocket 105 110

chain 5 having connected to it at intervals, 5 carton followers 6. The chain 5 is centrally arranged and has its upper stretch traveling between the upper side bars 3. It passes around a sprocket wheel 7 fixed to a main drive shaft 8 disposed transversely at the rear end of the main frame and journaled in suitable bearings. Power may be applied to this shaft 8 by means of a chain passing 10 around a driving sprocket wheel 9 or by any other suitable means.

At the front end of the frame, the main conveyer chain 5 passes around a sprocket wheel on a transverse shaft 10 journaled in 15 bearings which are slidable in guide brackets 11 and adjusted by means of screws 12, see Figs. 1^a and 2^a. These adjustable bearings permit the main conveyer to be tightened when necessary.

20 Each of the followers 6 (see Fig. 10) comprises a central portion at one end of which is provided a transverse plate 13 and at the other end a cross head 14, the extremities of which latter are provided with carton engaging arms or wings 15. The plates 13 are secured centrally to the chain 5, as shown at 17 in Fig. 9, and their ends are reduced to travel through track-ways or 25 grooves 18 provided in the side bars 3 as shown more clearly in Figs. 12 and 13. These track-ways are lined with metal wear plates and their upper portions are formed by carton supporting plates 19, which are secured to the upper surfaces of the bars 3 and upon which the cartons slide as they are 30 fed through the machine. By constructing the follower 6 in this manner it will be seen that as it travels between the upper side bars of the main frame it will be effectively 35 supported by the engagement of its plate 13 with the track-ways or grooves 18, and the arms or wings 15 on the ends of its cross head 14 will engage one carton in each of the rows and simultaneously move such cartons over the supporting plates 19.

40 To support the ends of the plates 13 as the conveyer chain 5 passes around the sprocket wheels at the ends of the main frame, circular supporting plates 20 are fixed to the shafts 8 and 10 as shown in Figs. 2, 2^a and 11; and to support the lower or return stretch of the conveyer chain 5 angle metal supporting rails 21 are secured to the uprights 2 or other portions of the 45 main frame for the reception of the ends of the plates 13, see Figs. 1 and 11.

At the front end of the supporting frame I provide two endless feed conveyers or belts 22 and means for simultaneously pushing 50 the cartons from these feed conveyers or belts to the plates 19 in advance of the followers 6. The belts 22 have their upper stretches disposed horizontally alongside of the forward ends of the plates 19 and in the 55 plane of the same. The belts pass around

pulleys 23, 24, the pulleys 24 being driving pulleys fixed to a transverse shaft 25 journaled in suitable bearings on the main frame. The shaft 25 is driven from the shaft 10 by sprocket chain gearing 26, a suitable tightening pulley 27 being provided as shown in Fig. 1^a, to permit the sprocket chain 26 to be tightened after adjustment of the shaft 10.

70 Cartons are placed on the forward portions of the feed belts 22, manually or otherwise, and said cartons are placed between opposing guide members or rails 28-29 (see Fig. 12). These guide rails are preferably arranged in pairs and carried by inverted U-shaped frame members 30 secured to the main frame as shown in Fig. 12.

75 The inner guide rails 28 are stationary and fixed to hanger bolts 31 depending from the frame members 30. The outer guide rails 29 are adjustable toward and from the rails 28 to permit cartons of different sizes to be handled by the machine; this adjustment of said rails being preferably effected by fixing them to hangers 32 which are adjustable in slots 33 in the frame members 30, clamping nuts 34 being provided on the threaded ends of the hangers 32 as shown in Fig. 12.

80 The mechanism for feeding or pushing 95 the cartons on to the supporting plates 19 (shown in Figs. 2^a and 3 to 5) comprises two laterally reciprocating push members 35 which operate in unison so that they simultaneously push one carton from each 100 feed belt on to the coating supporting plate. These push members are in the form of angular plates which have longitudinally extending portions to engage the cartons and push them inwardly or laterally on to 105 the supporting plates and outwardly projecting transverse portions 36 which latter serve as stop flanges to stop the streams of cartons on the feed belts while one carton from each row is being pushed laterally on 110 to the plates. These angular push members 35 are fixed to the inner ends of transverse bars or rods 37 mounted to reciprocate in inner and outer bearing posts 38-39 and having their outer ends connected by uprights bars 40 which latter carry buffers 41 to engage the bearing posts 39 and cushion the inward movement of the push members.

115 The lower rods 37 on each side of the machine carry adjustably mounted pivots 42 which are engaged by the slotted outer ends of arms 43 fixed to the upper extremities of upright shafts 44 journaled in suitable bearings on the main frame. The lower ends of the shafts 44 are provided with 120 radial arms 45 carrying at their outer extremities blocks 46 which are pivotally mounted at 47, see Fig. 4.

125 The blocks 46 are formed with transverse openings in which are adjustably secured 130

by means of set screws 48, the reduced forward ends of connecting links or rods 49. These rods 49 have enlarged flat rear ends as shown in Figs. 6 and 7 and they are slidably supported on a transverse shaft 50, the intermediate portion of which is journaled in bearings on the lower side bars 4 of the main frame and the end portion of which projects through elongated openings or slots 51 formed in said rods 49. Fixed to the ends of the shaft 50 adjacent the rods 49 are cams 52 (Fig. 1^a) which engage and actuate anti-friction rollers 53 carried by the rods 49 on opposite sides of the slots 51. The rollers 53 are mounted on adjustable journals 54, which latter are clamped in slots 55 formed in the rods 49 as clearly shown in Fig. 6. Owing to this construction it will be seen that when the shaft 50 is rotated the cams 52 will reciprocate the links or rods 49 in unison to rock the upright shafts 44 and the motion of the latter will be imparted to the push members 35, the latter reciprocating in opposite directions in unison.

For the purpose of preventing the cartons from being tilted and thrown over on their sides when they are pushed from the feed belts on to the supporting plates 19, I provide guard members 56 which are carried by push members 35 and spaced therefrom a distance sufficient to receive the cartons. The guard members 56 are in the form of vertically disposed plates having their upper ends clamped between flanged sleeves 57 which are slidably arranged on a transverse supporting rod 58 uniting the upper extremities of the two inner uprights 38. The flanged sleeves 57 receive the guard members 56 between them and they are bolted together and connected by angular arms 59 to the push members 35 as clearly shown in Figs. 4 and 5. The angular arms 59 have their inwardly extending, horizontal branches serving as one of the fastening bolts uniting the co-acting flanged sleeves 57, adjusting nuts 60 being provided on said arms 59 to adjustably connect the parts whereby each guard plate 56 may be adjusted toward and from the co-acting push member.

In order to stop the cartons in front of the push members 35 when the latter are in their retracted positions shown in Fig. 3, I provide upright stop members or plates 61 (Fig. 29), fixed to the upright portions of one of a series of inverted U-shaped frame members 62 (Fig. 4), which latter are similar to the frame members 30 and are arranged at intervals along the upper portion of the main frame for the purpose of supporting carton guiding rails and other parts.

The means for guiding the cartons along the supporting plates 19 are similar to the guiding devices described above, and each

one consists of pairs of superposed guide rails or rods 63, 64 (Figs. 2, 2^a and 13). The inner guide rails 63 are in the form of flat bars fixed to depending hanger bolts 65 in the frame members 62 as clearly shown in Fig. 13. The outer guide rails 64 are adjustably mounted, the upper one being a flat bar and the lower one a rod disposed in a plane slightly above the adjacent carton supporting plate 19. These outer guide rails 64 or rods 54 are fixed to adjustable hanger bolts 66, the upper ends of which are adjustable in slots in the frame members 62 as clearly shown in Fig. 19. Owing to this adjustment the space between the guide rails 64 may be varied to permit the machine to operate on different sized cartons.

Any means may be provided for receiving the finished cartons as they pass from beneath the rearmost sealing rollers 115 and out the rear end of the frame, but I preferably curve the guiding bars or rails 63, 64 laterally in an outward direction as indicated at 120 in Fig. 2, so that the cartons will be pushed laterally on to suitable moving conveyers, not illustrated.

If desired I may employ in connection with the carton feeding belts 22 manually operated stop devices such as shown in Fig. 14. On referring to this view it will be seen that 121 denotes an angular stop arm carried by one end of the lever 122 pivoted at 123 and having a handle at its free end. The lever 122 is adapted to be swung in a horizontal plane to move the lower angular end of the stop arm 121 into and out of the path of the cartons which are fed rearwardly by the belts 22. When the stop arm 121 is in the position shown in Fig. 21 the feed of cartons by the belts 22 against the stops 61 will be prevented. When the operator desires the feed to be resumed the lever 122 is oscillated to swing the stop 121 out of the path of the cartons.

In operation, it will be seen that when power is applied to either end of the main shaft 8 the main conveyor 5 will be actuated and the motion of the latter will be imparted to the carton feeding belts 22. The motion of the main shaft 8 will be imparted to the shafts 101 and 50 respectively, the motion of the shaft 101 being imparted by means of the sprocket chain gearing 100 to the glue applying mechanism. From the shaft 50 will be driven the lateral push members which feed the cartons from the belts 22 on to the supporting plates 19 in advance of the followers on the main conveyor 5, and from said shaft 50 will also be driven the cam shaft 86 of the frame carrying the oscillating glue applying rollers, and the shaft 72 of the second end flap folders. As the cartons are placed on the belts 22 they are carried rearwardly against the stops 61 and at the proper time the two

push members or plates 35 are simultaneously actuated in an inward direction to shift two cartons at a time, one from each of the belts 22 on to the supporting plates 19 in advance of the follower arms 15 on the advancing follower of the main conveyer. The cartons are then carried through the machine by the follower and their end flaps are successively folded, their side flaps 10 glued and successively folded and all of the flaps pressed down by the sealing rollers and the sealed cartons are discharged at the rear end of the machine.

From the foregoing it will be seen that 15 by reason of the continuous passage of two streams of cartons through the machine, the latter will have a large output and at the same time may be operated at a comparatively small cost and with little effort on the 20 part of the operator, the machine being entirely automatic in operation. By constructing and arranging the parts so that they may be adjusted with respect to each other, cartons of different sizes may be effectively handled by the machine. The improved means for supporting and feeding the cartons beneath the folding and gluing mechanism insures a regular feed of two 25 streams of cartons through the machine thereby rendering it reliable in operation and also giving it a large capacity as stated 30 above.

While I have shown and described in detail the preferred embodiment of my invention, it will be understood that changes in 35 the form, proportion and arrangement of parts and in the details of construction may be resorted to within the spirit and scope of the claimed invention.

40 I claim:

1. In a machine of the character described, the combination of means for supporting and guiding two streams of cartons, a main conveyer traveling between said guiding and 45 supporting means, two feed-conveyers to supply to said main conveyer, and means for simultaneously moving a carton from each feed-conveyer to said guiding and supporting means to be engaged by the main conveyer.

2. In a machine of the character described, the combination of two parallel belts for conveying two streams of cartons, two carton guiding ways within the planes of said 55 belts, a conveyer between the guideways provided with means for propelling cartons along the guiding ways, and means comprising transverse push members for simultaneously pushing a carton off each belt 60 upon the adjacent guideway.

3. In a machine of the character described, the combination of means for supporting and guiding two streams of cartons, a main conveyer to travel between said carton supporting 65 and guiding means, followers ar-

ranged at intervals on said main conveyer and provided with members to engage with cartons in both streams and push them through said carton guiding means, feed conveyers to supply cartons to said main 70 conveyer, and means for simultaneously pushing a carton from each feed conveyer into the path of the carton engaging members of a follower on the main conveyer.

4. In a machine of the character described, 75 the combination of means for supporting two streams of cartons, pairs of spaced guiding members for guiding two streams of cartons on said supporting means, means whereby the guiding members of each pair 80 may be adjusted toward and from each other for the reception of different sized cartons, a main conveyer to travel between the two carton supporting and guiding means, and provided at intervals with followers having 85 members to engage cartons and push them through said guiding means, and means for feeding cartons simultaneously to both members of a follower on the main conveyer.

5. In a machine of the character described, 90 the combination of a carton supporting plate, spaced carton guiding members adjacent the latter, means for adjusting one of said members toward and from the other to receive cartons of different sizes, and means 95 for feeding cartons to said guiding members.

6. In a machine of the character described, the combination of plates for supporting two streams of cartons, track-ways beneath 100 said plates, two pairs of spaced carton guiding members disposed above said plates, a main conveyer, followers secured at intervals to said main conveyer and each having a base plate, and a cross head terminating in 105 carton engaging wings, said base plate having its ends traveling in said track-ways, means for feeding cartons on to said carton supporting plates in advance of the carton engaging wings on the followers of the main conveyer.

7. In a machine of the character described, the combination of a supporting frame, transverse shafts, sprocket wheels upon the latter, a main conveyer chain passing around 110 said sprocket wheels, carton supporting plates arranged on the frame on opposite sides of the conveyer, track ways beneath said plates, carton guiding means above said plates, followers fixed at intervals to said conveyer chain and each consisting of a 115 base plate having its ends arranged to travel through said track ways and a cross head provided at its extremities with carton engaging wings, follower supporting disks fixed to said shafts on opposite sides of said 120 sprocket wheels and adapted to engage the base plates of the followers, and means for feeding cartons to the followers of the main conveyer.

8. In a machine of the character described, 125

the combination of plates for supporting two streams of cartons, track-ways beneath said plates, two pairs of spaced carton guiding members disposed above said plates, a 5 main conveyer, followers secured at intervals to said main conveyer, and each having a base plate and a cross head terminating in carton engaging wings, said base plate having its ends traveling in said track-ways, 10 carton feeding belts arranged adjacent the forward ends of the carton supporting plates, spaced carton guiding members arranged above said belts, transversely reciprocating push members for feeding the cartons from said belts on to said plates in 15 advance of the follower wings, means for simultaneously operating said push members, stops carried by said push members for preventing the cartons from tilting when 20 they are pushed upon said plates, and retractable stops disposed above said belts for checking the feed of the cartons.

9. In a machine of the character described the combination of means for guiding, supporting and feeding two streams of cartons, 25 two feed conveyers parallel therewith and in vertical planes outside of those of the guiding means, two transverse plungers in line with each other for pushing cartons off the feed conveyers upon the guiding means, and means for simultaneously operating said plungers comprising two vertical shafts, a crank arm on each shaft adjustably connected to one of the plungers, and means for 30 simultaneously oscillating the two vertical shafts.

10. In a machine of the character described, the combination of means for guiding, supporting and feeding two streams of 40 cartons, two feed conveyers parallel therewith and in vertical planes outside of those of the guiding means, two transverse plungers in line with each other for pushing cartons off the feed conveyers upon the guiding means, and means for simultaneously operating said plungers comprising two vertical shafts, a crank arm on each shaft adjustably connected to one of the plungers, a second 45 crank arm on each vertical shaft, a transverse shaft, a cam on each end thereof and a link simultaneously operated by each cam and connecting it with the second crank arm of one of the vertical shafts.

11. In a machine of the character described the combination of four parallel 55 tracks or guideways for cartons, a transverse shaft, a cam at each end thereof, a vertical shaft on each side of the machine, a lower crank arm on each vertical shaft, a link connected with each crank arm at one end and

a cam at the other for simultaneously oscillating the two shafts, an upper crank arm on each shaft, and a transverse plunger connected to each upper crank arm.

12. In a machine of the character described, the combination of a supporting frame, plates for supporting two streams of cartons, a main conveyer having followers provided with wings to travel over said plates and engage the cartons, inverted U-shaped members disposed above said plates and provided in their upper portions with slots, depending hangers carried by said U-shaped members, means for adjustably clamping certain of said hangers in said 75 slots, and carton guiding rails carried by said hangers.

13. In a machine of the character described, the combination of means supporting two rows of cartons, devices guiding the 80 cartons along said supporting means, a single conveyer and followers on said conveyer engaging and advancing the cartons in two rows along said supporting means.

14. In a machine of the character described, the combination of two carton supporting tracks or ways, a conveyer, and followers on said conveyer each simultaneously engaging and advancing two cartons one on 85 each track or way.

15. In a machine of the character described, the combination of a single conveyer, a plurality of carton-guiding lanes or channels, and a plurality of followers on said conveyer simultaneously engaging and 95 advancing the cartons in said lanes or channels.

16. In a machine of the character described, the combination of a single conveyer, a plurality of followers thereon, and 100 means simultaneously feeding a plurality of cartons in front of each follower whereby the single conveyer simultaneously advances a plurality of streams of cartons.

17. In a machine of the character described, the combination of means supporting two rows of cartons, devices guiding the cartons along said supporting means, a single conveyer element located in a vertical plane passing between said two rows of cartons, and followers on said conveyer engaging and advancing the cartons in two rows 110 along said supporting means.

In testimony whereof I have hereunto set my hand in presence of two subscribing witnesses.

FRANK B. MARTIN.
